UNITED STATES PATENT OFFICE.

NATHAN HATCH, OF ALBANY, NEW YORK.

UNION SUIT.

1,110,053.

Specification of Letters Patent. Patented Sept. 8, 1914.

Application filed December 20, 1913. Serial No. 807,826.

To all whom it may concern:

Be it known that I, NATHAN HATCH, a citizen of the United States, and a resident of Albany, county of Albany, and State of New York, have invented certain new and useful Improvements in Union Suits; and I do declare the following to be a full, clear, and exact description of the invention, such as will enable others skilled in the art to 10 which it appertains to make and use the same, reference being had to the accompanying drawings, and to the letters and figures of reference marked thereon, which form part of this specification.

15 The invention relates to an article of wearing apparel, more particularly to union undergarments for men, boys and misses.

One of the objects of the invention is to construct a union suit to fit the body of the 20 wearer perfectly and securely and to make it very easy to put on and take off the person of the wearer.

Another object is to construct a garment in which it is not necessary to provide the 25 objectionable lines of buttons and button-holes or securing means which are used in men's garments and extend from the neck thereof to the crotch.

Another object is to provide a union suit 30 which is practically integral in the body portion thereof, no fastening means such as buttons, buttonholes and the like being utilized in the front of the garment, or in vertical lines up and down the back.

35 Another object is to provide a union undergarment in which the fastening means are of minimum number and arranged at the back of the garment substantially at the waist line thereof.

40 Other objects will appear from the following description and claims.

The garment is especially useful for persons engaged in athletics, such as horse-back riding and the like. The construction 45 is such that the upper portion is practically continuous around the body, similar to ordinary sweaters or athletic undershirts, and the lower or leg portions of the garment are also continuous and are integral with the 50 front part of the shirt portion and amply secured at the rear by the use of only a few, usually three, buttons or fastening means.

The garment is so constructed that in putting 55 it on the body, the legs of the wearer may be inserted into the leg portions in a

manner similar to the ordinary way in which trousers are put on, and then the upper portion is placed upon the body of the wearer over the head in a manner similar to the way in which a sweater or athletic shirt is put on the body of the wearer. The rear portions of the garment are then closed and fastened by the securing means provided at suitable places.

This invention is a species of the generic 65 invention described and claimed in my co-pending application Serial No. 807,825, filed December 20, 1913.

Referring to the drawings: Figure 1 is a view in perspective of the rear of the garment as placed upon the body of the wearer. Fig. 2 is a similar view of the front of the garment. Fig. 3 is a view of the rear of the garment with the lower flap unfastened and hanging downward. Fig. 4 is a 75 similar view in which a corner of the upper flap is in raised position. Fig. 5 is a detail view of the front of the garment showing the arrangement for the fly. Fig. 6 is a pattern of one of the seat portions. 80

In the detailed description the similar reference characters indicate corresponding parts.

The garment may be made of either woven or knitted fabric, and except for the features 85 of construction which form my invention, the garment is made in the usual way, namely, the leg portions may be short or long, the arm portions short or long, and the arm and leg ends are ribbed as usual, 90 the neck being finished in the usual way.

On the drawings, A represents the integral body portion of the garment, B the leg portions, C the upper back flap and D the lower back flap.

The body portion of the garment in the front and in the rear is made substantially of one continuous piece, the same being secured the inside of each leg as indicated at 95 a, a', a. In the rear of the garment I provide slits b, b' and c, c', situated respectively on opposite sides of the back, extending from a point a short distance below and to the rear of the arm pits on each side to a point, as desired, at the sides of the hip portion. There is therefore formed a back flap indicated by b b', c c'. At points about one-third the distance down on each side I construct buttonholes or other suitable fastening means f f. The edges of this flap and 105 110

the sides of the slit portions of the garment are finished in the usual way. The lower portion of this flap may be integral with the material forming the back of the garment or 5 may be in a separate piece and secured thereto by a line of stitching. Also in the rear of the garment at suitable points on each side just below the hip, I secure at d, d' the lower portion of a seat flap. The outer 10 edges of this flap are finished as usual and the upper edge is provided with a band or belt portion k , made of the same material as the garment or of other suitable material, in which are several buttonholes, or fastening 15 means e, e' , arranged in lines perpendicular to each other so that the fastening may be adjustable. The seat flap is formed from extensions of the material forming the rear of the leg portions and the insert shown in Fig. 20 20 6, forms a seat portion as indicated at g, g', g'' . The garment is provided with overlapping yet open construction to form the fly. The edges of the back flap also overlap at the side slits.

25 A row of buttons or other fastening means is provided across the back on the upper flap, shown at h . While I have shown buttons on one portion of the garment and buttonholes on the other, it is evident that the 30 positions of the two, which make up the fastening means, may be reversed, or other suitable fastening means may be used in place of buttons and buttonholes.

As above stated, the garment may be applied to the person by the wearer stepping 35 into the leg portions thereof and then lifting the rear of the shirt or body portion so that it may be placed over the head and the arms inserted at the same time into the arm 40 holes or arm portions. The upper back flap is then secured to the sides of the main portion of the garment at f, h , shown in Fig. 3, and then the lower rear or seat flap is raised 45 and secured in the usual way by the fastening means provided therefor, the said fastening means being secured together and the center fastening means being also secured if desirable.

If desired, by means of the several rows of 50 fastening means provided in the waist band of the seat flap, the position of the garment

may be adjusted to suit the comfort and necessities of the wearer.

I have illustrated and described the embodiment of my invention which I believe to 55 be the one best subserving the several objects which I have in view. Nevertheless, it is to be understood that the illustration and description is exemplary and that changes 60 may be made in the details thereof, and also that the invention may be otherwise and variously embodied without departing from its spirit or its scope as defined in the subjoined claims.

The invention is not restricted as to details except as these are definitely expressed in the claims considered severally.

Having now described my invention, what I claim as new and desire to secure by Letters Patent is:

1. A union suit comprising a body portion and leg portions, having a vertical slit at each side from a point adjacent to the arm to a point adjacent to the hip, and the back provided with two oppositely extending 75 flaps which are secured one to the other and to the main portion of the garment adjacent to the side slits as described.

2. A union suit comprising an integral front and a slitted back, the slits being arranged at each side thereof up and down the body of the wearer from a point adjacent the arm to a point adjacent the hip, across the garment from hip to hip, said slits forming an opening situated entirely in the rear 85 of the garment, to form a back flap, a seat flap, each of the flaps being separated from each other at the medial line, and fastening means on the flaps for detachably securing the one to the other, the said flaps when closed covering the said opening through 90 which the body of the wearer is inserted to place the garment thereupon.

In witness whereof I have hereunto set my hand at borough of Manhattan, city and 95 State of New York, this 17th day of December, 1913.

NATHAN HATCH.

In presence of—

H. CROCHERON,
ISABEL R. RICHARDS.
